UNITED STATES PATENT OFFICE.

CHARLES R. DINGEE, OF LOSTANT, ILLINOIS, ASSIGNOR OF ONE-HALF TO ALEXANDER C. KELSO, OF LOSTANT, ILLINOIS.

SELF-LOCKING WHIP-SOCKET.

1,073,967.

Specification of Letters Patent. Patented Sept. 23, 1913.

Application filed December 14, 1912. Serial No. 736,800.

To all whom it may concern:

Be it known that I, CHARLES R. DINGEE, a citizen of the United States of America, residing at Lostant, in the county of LaSalle 5 and State of Illinois, have invented certain new and useful Improvements in Self-Locking Whip-Sockets, of which the following is a specification, reference being had therein to the accompanying drawing.

10 This invention relates to whip sockets, and the principal object of the invention is to provide a whip socket which is so constructed that the whip may be locked in the socket thus preventing its removal by un-15 authorized persons.

Another object of the invention is to provide an improved type of lock which is so constructed that it may be held in a released position until it is desired to have the whip 20 locked.

This invention is illustrated in the accompanying drawings, wherein:—

Figure 1 is a view of a whip in a socket with the locking means in a locked position. 25 Fig. 2 is a view similar to Fig. 1 with the locking means in a position to permit withdrawal of the whip. Fig. 3 is a section along the line 3—3 of Fig. 1.

Referring to the accompanying drawings, 30 it will be seen that this invention comprises a socket 10 which is preferably cylindrical in shape and provided with a vertically extending opening 11 in one side. A housing 12 extends from the socket 10 and incloses 35 the opening 11 as clearly shown in Fig. 3. This housing contains the locking mechanism and is provided in its outer edge with an opening 13 so that after the locking means has been moved to a released position, 40 it may be returned to the locked position.

The locking means is mounted in the housing 12 and comprises a vertical bar 14 which is pivotally mounted upon a pivot pin 15. An arm 16 extends from the upper end of 45 the bar 14 and is provided with a beveled end so that when a key is inserted into the housing with its inner end engaging the pin 17 and turned, the key will engage the beveled end of the arm 16 and thus lock the 50 bar 14 against the tension of its spring to release the whip. The spring comprises a resilient strip which is coiled intermediate its length to form the eye 18 having the arms 19 and 20 extending therefrom. The eye is 55 secured in a recess 21 by means of the pin

22 and the arm 19 is secured to the outer face of the housing by means of a suitable rivet. The arm 20 extends across the housing and is provided with a bent end 23 which is secured to an extension 24 leading 60 from the bar 14. This spring normally holds the bar 14 in the position shown in Fig. 1 so that its inner end will pass through the opening 11 and into the socket 10. It will also be noted that upon inserting the whip 65 25 in the socket that the downward pressure will cause the head 26 to rock the bar upon its pivot point, the spring 20 returning the bar to the position shown in Fig. 1 thus preventing the removal of the whip. A latching 70 bar 27 extends from the lower end portion of the bar 14 and into the opening 13. This bar is provided intermediate its length with a notch 28 in which is adapted to engage a pin 29 to hold the locking means in a 75 released position.

When using this device the whip is inserted in the socket and will move the locking means sufficient to permit it to assume the position shown in Fig. 1 but will not move 80 it to such an extent as to cause the locking means to be held in the position shown in Fig. 2. The whip will thus be securely held in the socket and prevented from being removed. When it is desired to use the whip 85 a key is inserted in the housing and turned so that the bar 14 will be rocked upon its pivot point and the pin 29 passed into the notch 28 thus holding the locking means in a released position. The whip can then be 90 removed whenever desired and replaced without it being necessary to turn the key every time it is desired to withdraw the whip. When desired to again lock the whip in the socket it is simply necessary to raise 95 the outer end of the latching bar 27 thus releasing the bar 27 from the pin 29 and the spring will then return the locking mechanism to a locked position.

Having thus described the invention, what 100 is claimed as new, is:—

1. A whip socket provided with a vertically extending slot in one side, a housing inclosing the slot and provided with an opening in its outer face, a locking bar pivotally mounted in said housing and provided with an arm extending from its upper end, an extension leading from said bar intermediate its length, a spring secured to said housing and having its remaining end se- 110

cured to said extension whereby the lower end of said bar will be normally caused to pass through said slot into said socket, a pin passing transversely through said housing, 5 and a latching bar extending from said locking bar above said pin and through the opening in said housing, said latching bar being provided with a notch in which said pin is adapted to fit when said locking bar 10 is rocked upon its pivot point to hold said locking bar in a released position.

2. A whip socket provided with a vertically extending opening, a housing carried by said socket and inclosing said slot, said 15 housing being provided with an opening in its outer face, a locking bar pivotally mount-

ed in said housing, resilient means for normally holding said locking bar with its lower end extending through the slot into said socket, a pin extending transversely through said housing, and a latching bar extending from said locking bar above said pin and through the opening in said housing, said latching bar being provided with a notch in which said pin is adapted to fit to hold 25 said locking bar in a released position.

In testimony whereof I hereunto affix my signature in presence of two witnesses.

CHARLES R. DINGEE.
